SAMUEL N. HALL, OF HOUSTON, TEXAS.

WRENCH.

1,107,936.

Specification of Letters Patent. Patented Aug. 18, 1914.

Application filed August 23, 1913. Serial No. 786,282.

To all whom it may concern:

Be it known that I, SAMUEL N. HALL, a citizen of the United States, residing at Houston, in the county of Harris and State of Texas, have invented certain new and useful Improvements in Wrenches, of which the following is a specification.

This invention relates to new and useful improvements in wrenches, and has particular relation to wrenches of the chain type.

The object of the invention is primarily to provide a double acting wrench in which both of the jaws are similar and interchangeable and provided with additional sets of teeth whereby the life of the jaws is increased, and further comprehends a handle of a novel shape and method of attachment to the jaws, therein embodying an improvement over the wrench disclosed in Patent Number 889,246 heretofore issued to M. E. Layne and myself by the United States Patent Office.

With the above and other objects in view, the invention has particular relation to certain novel features of construction, operation and arrangement of parts, an example of which is given in this specification and illustrated in the accompanying drawings, wherein—

Figure 1 is a side elevation of the wrench, as applied to a pipe. Fig. 2 is a fragmentary view of the operating end of the handle. Fig. 3 is a fragmentary plan view thereof. Fig. 4 is a sectional end view of my preferred form of the wrench. Fig. 5 is a plan view of the jaw employed in said form. Fig. 6 is a sectional end view of a modified form of the wrench, and Fig. 7 is a plan view of the jaw used in said modified form.

Referring to the drawings, the numeral 1 represents a handle provided with an arculate section 1^a, the portions 1^b and 1^c of the handle being disposed in the same plane for a purpose later set forth. As shown in Fig. 3, the end 1^b is enlarged and provided with the slot 3 and projecting upwardly from the free end thereof are the hooks 4, 4, one on each side of the slot 3, for detachably engaging the chain 5. The chain is of the type ordinarily employed in devices of this kind, wherein the pintles 6 project past the side plates 7, which construction adapts the chain to fit between the sides of the hooks 4, while the ends of the pintles project out laterally a sufficient distance to engage the front sides of said hooks.

The numeral 8 designates the jaw plates of my preferred form of wrench, one of which is fitted to each side of the enlarged end 2 of the handle and clamped in position 60 by means of the transverse bolt 9 passing through said jaw plate and the enlarged end 2. Each of the plates is provided at its opposite side with two sets of teeth 10 so that after one side of the jaw plates is worn out 65 they may be turned over and the unworn sets of teeth brought in to position for use. The recess 11 is provided intermediate of the sets of teeth 10 on each side of the jaw plates in order to permit the transfer of the pipe 70 from one set of teeth to the other without releasing the chain and in order to provide the slack in the chain for its release when the pipe is placed in such central recess 11.

The inner side of each of the jaw plates 75 is provided with two lengthwise shoulders 12 spaced apart and having their inner sides abrupt, and between these shoulders the enlarged end 2 of the handle snugly fits, as shown in Fig. 4, whereby the plates are held 80 rigidly against turning relatively to the handle when the clamp bolt 9 is tightened. It will be noted that the jaw plates are symmetrical on opposite sides of the transverse center line a—a and also on opposite sides of 85 the longitudinal line b—b, which construction provides for the interchangeability of the jaws from one side of the handle to the other and also provides for turning the jaws over, so that after the teeth on one side have 90 been worn those on the other side may be brought in to position for use. The end of the grip chain 5 is permanently secured to the handle 1, as shown in Fig. 2. The sides of the handle near the end 2 are wedged out 95 on each side, forming recesses in which the respective members of a double link of the chain rest and a pin or rivet passes through said links and the handle, said pin passing also through aligned orifices 15 in the jaws 100 and strengthening the attachment of the handle to the jaws.

In Fig. 7 I have shown a modified form of the jaw plate, which is designated by the numeral 8'. This jaw plate has a lengthwise, centrally located rib 13 which fits into a corresponding lengthwise groove 14 in the side of the enlarged end 2 whereby the plates are held rigidly against turning when clamped on the handle by means of the bolt 110 9 as hereinbefore explained. With the exception of the method of securing the jaw

plates against turning relative to the handle, the two forms of wrench herein shown and described are precisely similar.

In screwing and unscrewing pipe, it is often necessary to, at different times, turn the pipe in opposite directions and, to facilitate the work, it is desirable that a wrench be employed by means of which the pipe may be turned either way without disengaging the wrench therefrom. As illustrated in Fig. 1 the wrench herein described may be used to turn the pipe on which it is engaged in either direction. When the pipe is in the position, relative to the wrench, shown in full lines in Fig. 1, by a downward manipulation of the handle the pipe may be turned in one direction and when it is desired to turn it in the opposite direction, it may be shifted to the position shown in dotted lines in Fig. 1, without disengaging the chain 5, and by an upward manipulation of the handle 1, the said pipe will be turned in the opposite direction. The chain 5 must necessarily have a certain amount of slack, which must be taken up before the chain 5 will grip around and turn the pipe and consequently the handle 1 must have a certain range of movement in order to permit the slack to be taken up before the handle comes in contact with the chain. For this purpose the handle near its operating end has an arcuate, or curved section the concave or recessed side of which permits the required range of handle movement it, of course, being understood that any other manner of forming the handle relatively to the gripping plates may be adopted without departing from the spirit of the invention.

The improvement may be briefly described as a straight handle, having a hooked head end portion, and a curved connecting portion affording, on the working side a recess, and a pair of double ended tapering trebly reversible interchangeable jaw plates having on one face handle embracing ribs, and so secured to the head as to bring one edge of their tapering inner ends alongside the head portion of the bend of the recess, and a chain substantially in the longitudinal median plane of the handle, said chain anchored at one end to the head, and adjustably attached to the hooks by its outer portion, and, in use, playing partly within the space afforded by the recess.

What I claim is:—

1. A pipe wrench comprising a handle provided intermediate of its ends with a curved portion forming a recess, a pair of elongated interchangeable jaw plates clamped to the opposite sides of the handle, and each provided on its opposite longitudinal sides with two sets of oppositely acting teeth, arranged so that one set operatively engages the pipe when the handle is turned in one direction, and the other set operatively engages the pipe when the handle is turned in the opposite direction.

2. A pipe wrench comprising a handle provided intermediate of its ends with a curved portion forming a recess, a pair of elongated interchangeable jaw plates clamped to opposite sides of the handle, engaging means carried by each jaw plate and extending lengthwise thereof and engaging with said head and locking the jaw plates rigidly against turning relative to the handle, each jaw plate being provided on its opposite longitudinal sides with two sets of oppositely acting teeth arranged so that one set operatively engages the pipe when the handle is turned in one direction and the other set operatively engages the pipe when the movement of the handle is reversed, together with a grip chain anchored to the end of the handle adjacent to the jaw plate.

3. A pipe wrench comprising a handle provided intermediate of its ends with a curved portion forming a recess, a pair of elongated interchangeable jaw plates clamped to opposite sides of the head, engaging means carried by each jaw plate and extending lengthwise thereof and engaging with said head and locking the jaw plates rigidly against turning relative to the handle, each jaw plate being provided on its opposite longitudinal sides with two sets of oppositely acting teeth arranged so that one set operatively engages the pipe when the handle is turned in one direction and the other set operatively engages the pipe when the movement of the handle is reversed, together with a grip chain anchored to the end of the handle adjacent to the jaw plates.

4. A pipe wrench, a handle having at one end means for detachably engaging a grip chain, a pair of elongated interchangeable jaw plates clamped to the opposite sides of the handle, and each provided on its opposite longitudinal sides with two sets of oppositely acting teeth, arranged so that one set operatively engages the pipe when the handle is turned in one direction, and the other set operatively engages the pipe when the movement of the handle is reversed, together with a grip chain anchored to the end of the handle adjacent to the jaw plates, a section of said handle adjacent to the jaw plates being raised out of alignment with said plates to permit said chain to pass between the pipe and said raised section.

5. A device of the character described including a handle, means carried by one end for detachably engaging a grip chain, a curved section adjacent to said engaging means affording on its working side, a re-

cess, a pair of double ended, tapering, reversible interchangeable jaw plates, handle engaging means on one face of each jaw plate, said jaw-plates being so secured to the handle as to bring one edge of their tapering inner ends alongside of the said recess, and a chain substantially in the longitudinal median plane of the handle, said chain being anchored at one end to the handle, intermediate of said chain engaging means, and recess, and adjustably attached at its other end to said last mentioned means, and, in use, playing partly within the space afforded by the recess.

6. A device of the character described including a handle having a hooked head end portion and a curved connecting portion, affording, on its working side, a recess, a pair of double-ended, tapering, trebly reversible interchangeable jaw-plates having on one face handle engaging means and so secured to the head as to bring one edge of their tapering inner ends alongside of the head portion of said recess, and a chain substantially in the longitudinal median plane of the handle, said chain being anchored at one end to the head, adjustably attached to the hooks of said head by its outer end, and, in use, playing partly within the space afforded by said recess.

7. A device of the character described including a handle, having one end enlarged into a head, hooks carried by said head for

detachably engaging a grip chain, a curved section connecting said head to the handle, affording on its working side, a recess, a pair of double-ended, tapering, reversible, interchangeable jaw plates, so secured to the head as to bring one edge of their tapering inner ends alongside of the head portion of the recess, ribs carried by the inner face of each jaw plate and embracing said head and a chain substantially in the longitudinal median plane of the handle, said chain being anchored at one end to the head, adjustably attached to said hooks by its outer portion, and, in use, playing partly within the space afforded by said recess.

8. A pipe wrench comprising a handle, a pair of interchangeable jaw plates secured on opposite sides of the handle at one end thereof, a gripping chain pivotally attached at one end to said handle, and means for detachably fastening the free end of said chain to said handle, said handle being provided adjacent to its connection with said plates with an arcuate portion to permit greater movement of said handle.

In testimony whereof I have signed my name to this specification in the presence of two subscribing witnesses.
